CLAIM

The ornamental design for a carrier for containers, as shown and described.

DESCRIPTION

FIG. 1 is a rear, top perspective view of a carrier for containers showing my new design.

FIG. 2 is a front, bottom perspective view thereof.

FIG. 3 is a front elevation view thereof.

FIG. 4 is a right elevation view thereof; the left elevation view is a mirror image of the right elevation view.

FIG. 5 is a rear elevation view thereof.

FIG. 6 is a top plan view thereof.

FIG. 7 is a bottom plan view thereof; and,

FIG. 8 is a plan view thereof shown in an unfolded configuration.

The broken lines are shown for the purpose of illustrating both parts of the article as well as environmental subject matter. None of the broken lines form part of the claimed design.
